STREAMLINED CIGARETTE HOLDER

Philip J. Schoenberger, St. Paul, Minn.

Application November 29, 1954, Serial No. 33,293

Term of patent 14 years

(Cl. D85—2)

Fig. 1

Fig. 2

Fig. 3

Fig. 4

I claim:

The ornamental design for a streamlined cigarette holder, as shown.
